(57) **CLAIM**

The ornamental design for a retractable leash strap as shown and described.

DESCRIPTION

FIG. 1 is a perspective view of a retractable leash strap, showing my new design;

FIG. 2 is a top plan view thereof;

FIG. 3 is a bottom plan view thereof;

FIG. 4 is a right side view thereof;

FIG. 5 is a left side view thereof;

FIG. 6 is a front view thereof; and,

FIG. 7 is a rear view.

The broken lines and unshaded areas in the drawings depict portions of the retractable leash strap that form no part of the claimed design.
